UNITED STATES PATENT OFFICE.

JOHN C. MERWIN, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES J. W. TOWNE, F. B. TOWNE, E. S. TOWNE, J. M. TOWNE, AND F. W. WILSON.

LOOSE-LEAF BINDER.

1,192,923.

Specification of Letters Patent.

Patented Aug. 1, 1916.

Application filed July 31, 1915. Serial No. 42,987.

To all whom it may concern:

Be it known that I, JOHN C. MERWIN, a citizen of the United States, residing at the city of Holyoke, county of Hampden, State 5 of Massachusetts, have invented certain new and useful Improvements in Loose-Leaf Binders; and I do declare the following to be a full, clear, and exact description of the invention, such as will enable others skilled 10 in the art to which it appertains to make and use the same.

The present invention relates to new and useful improvements in loose-leaf binders and it has for its primary aim to provide an 15 improved guiding means for the side clamping members of a binder which will efficiently operate in maintaining the clamping members steady during sliding thereof.

The invention further resides in a simple 20 construction wherein is provided flat end bridge pieces with which coöperate the turned over portions of the slideable clamping members of the binder for guiding the same.

25 For a full understanding of the invention reference is had to the following specification and claims and the accompanying drawing wherein like numerals of reference designate corresponding parts throughout 30 and in which:

Figure 1 is an elevation of the back of a loose leaf binder embodying the invention; Fig. 2 is a transverse section thereof taken on line 2—2 of Fig. 1; Fig. 3 is a fragmentary longitudinal section on line 3—3 of Fig. 35 1; and Fig. 4 is a fragmentary perspective of one of the side clamping members.

The type of binder on which this invention is an improvement is shown in Patent 40 No. 1,085,328 granted to E. H. Elder, January 27, 1914. A binder of this style comprises a back plate 1 having angular ends 2 and centrally arranged bearing blocks 3 secured to the back plate and in which is journaled an operating rod 4. This rod is provided with right and left screw threads with which nuts 5 engage whereby on rotation of the rod the nuts will move in opposite directions, as is obvious.

50 The invention comprises a flat bridge piece

or plate 6 fixed on each bearing block 3 in parallel and spaced relation with the adjacent end 2. Slidably coöperating with the respective bridge pieces are the lips 8 which are formed by the turned over ends of side 55 clamping members 7 and which slidably engage the respective bridge pieces to steady and guide the clamping members in their lateral sliding movement. These lips operate in the space between the bridge pieces 60 and the adjacent ends 2 and coöperate with the bridge pieces to reinforce the structure. Each clamping member is curved upwardly and inwardly (Fig. 4) to permit of the member sliding inwardly on the flat bridge 65 pieces which are received in the formed pocket 9. Above the pocket 9 the clamping member is extended vertically to provide a flanged support 10 to which the covers, not shown, may be hinged as at 11. Extending 70 inwardly from the opposing supports 10 of the clamping members are the usual tubular posts and rods 12, 13, telescopically coöperating with each other. Cap plates 14 are secured to the ends of the clamping members 75 and extend over the lips 8 to move therewith between the bridge pieces and ends of the back plate. A pair of links 15 pivotally connects each clamping member to the nuts 5. It is obvious that on turning the rod 4 by 80 key 16, the nuts will accordingly separate or move toward one another, which, through the pairs of links 15, will correspondingly open or close the sliding clamping members 7. 85

The two end bridge pieces coöperating with the turned over lips render the binder substantial and practical throughout as well as efficient in operation.

What is claimed is:

1. In a loose-leaf binder, a back plate having angular ends, bearing blocks secured to the plate adjacent the ends thereof, flat bridge pieces secured to the blocks in spaced relation to the ends of the back plate, side 95 clamping members having their ends turned over to form lips slidably engaging with the respective bridge pieces and operating between the latter and the adjacent ends of the back plate, each clamping member being 100

provided with a pocket to receive the bridge pieces during closing movement, and operating mechanism journaled in the bearing blocks and connected to the clamping members.

2. In a loose leaf binder, in combination, a back plate having upturned ends, bearing blocks with bridge plates secured near said ends, and movable side clamping members

having inturned flanges movably engaging 13 with the outer edge of said bridge plates.

In testimony whereof I affix my signature in presence of two witnesses.

JOHN C. MERWIN.
